X-RAY TUBE SAFETY DEVICE

Edwin R. Goldfield, University Heights, and Jack Ball, Cleveland, Ohio, assignors to The Picker X-Ray Corporation Waite Manufacturing Division, Inc., Cleveland, Ohio, a corporation of Ohio

Original application July 20, 1946, Serial No. 685,095. Divided and this application November 2, 1948, Serial No. 57,988

5 Claims. (Cl. 250—95)

1

This invention relates to improvements in control circuits for X-ray tubes and more particularly to improvements in safety devices for preventing injury to X-ray tubes by overloading the same.

An object of the present invention is to provide means for preventing an overly long exposure combined with an excessive kilovoltage applied to the tubes.

Another object of the present invention is to prevent an excessive combination of time of exposure plus the milliamperage load on the tubes.

Still another object of the invention is to provide any excessive combination of time, kilovoltage, or milliamperage so as to overload the tube to the point of injury.

Another object of the present invention is to provide control means preventing overloading of the X-ray tube by an excessive combination of kilovoltage together with a second control factor which includes the product of the milliamperage load on the X-ray tube times the number of seconds the tube is energized.

Another object of the present invention is to protect the X-ray tube against overloading by a series of exposures repeated at short time intervals, no one of which is sufficient in itself to overload the tube, but the cumulative results of which would cause overheating of the X-ray tube anode and injury to the tube. By arranging a control factor in step with the heat dissipation factor of the X-ray tube anode, we build up the control factor at the same rate as the heat accumulation factor of the X-ray tube anode and thus utilize our novel control means to prevent the cumulative overloading mentioned above.

Other objects and advantages of the present invention will be apparent from the accompanying drawings and description, and the essential features thereof will be set forth in the appended claims.

In the drawings,

Fig. 1 is a wiring diagram showing one form of our device wherein the product of the milliamperage load on the X-ray tube times the number of seconds the load is applied is utilized in a control circuit;

Fig. 2 is a modification of the circuits of Fig. 1 for protecting the X-ray tube against accumulative effect of short exposures repeated with only short time intervals between them; while

Fig. 3 is a modification of the circuits of Fig. 2

2

and shows another means of accomplishing the same purpose.

An X-ray tube will take a definite maximum loading which is a function of the milliamperage, the kilovoltage and the time for a definite load limit. If any one of the above is increased, then it is necessary to decrease at least one of the other two factors.

In Fig. 1 we have shown an auto-transformer 10 supplied with electrical energy from the circuit L₁, L₂. Suitable taps connect leads 11 and 12 with the primary 13a of a high tension transformer 13. The secondary 13b of this transformer is connected by suitable leads with the X-ray tube 16 in the usual manner. The mid-portion of the secondary circuit of the transformer is grounded as shown and a correction for the milliamperage load on the tube is inserted at this point as will be presently described. An exposure is initiated by closing push button 18 to energize relay 22 which attracts relay armature 22a, completing the high tension transformer circuit through the normally closed armature 25b of relay 25. The filament of X-ray tube 16 is supplied with current from the source L₅, L₆ through transformer 61. The time control tube 26' is of the gas-filled triode type having a hot or cold cathode 26a', a plate 26b' and a control grid 26c'. The power supply for this tube may be a suitable source of alternating or rectified current supplied to lines 16 and 17 by suitable means not shown. Line 18 from the source 16 through relay 25 to plate 26b' completes the circuit for this tube.

In circuit with the control grid 26c' is a condenser 32 which is short circuited through lines 39 and 40 and the normally closed armature 22b of relay 22 when an exposure is not initiated. This keeps the condenser 32 fully discharged until an exposure is started.

When push button 18 is closed, relay 22 attracts armature 22b and opens the circuit of condenser 32 which then begins to charge, this condenser charging period timing the exposure.

In circuit with the voltage supply for grid 26c', and determining the time interval necessary to charge condenser 32, are control elements for compensating for changes in the kilovoltage applied to the high tension transformer 13, another compensation for the milliamperage load on the X-ray tube, and a third compensation factor which takes into account the time the X-ray load is applied to the tube.

The compensation for changes in kilovoltage applied to the X-ray tube include the transformer

62 which has a primary 62a connected by lines 63 and 64 across lines 11 and 12 which supply transformer 13. A variable resistor 65 is supplied to provide necessary adjustments. The secondary 62b of this transformer is in circuit with condenser 32 as will presently appear.

The compensation for changes in the milliamperage load on the X-ray tube is supplied in the central secondary circuit of transformer 13 by means of transformer 66. The primary 66a of this transformer is connected by lines 67 and 68 in the central secondary circuit of transformer 13 through variable resistor 69. The secondary 66b of this transformer is in circuit with condenser 32. The circuit for charging condenser 32 includes a portion of line 39, variable resistor 70, line 71, transformer secondary 62b, line 72, transformer secondary 66b, line 73, a rectifier 74, and line 75. The rectifier 74 may be a dry disc type rectifier or a tube so as to apply a positive charge to the condenser 32.

The rate of accumulation of the charge on condenser 32 and therefore on the control grid 26c' of the trigger tube 26' is a function of the adjustable resistor 70. This resistor 70 introduces the time element in the control circuit. Thus, with a given resistor setting at 70, the higher the milliamperage which flows through the X-ray tube, the sooner condenser 32 becomes charged up to the critical value of the trigger tube 26', so as to cause the tube to fire completing the circuit from cathode 26a' to plate 26b' to energize relay 25 which thereupon attracts the armature 25b and opens the circuit to transformer 13 so as to stop the exposure.

In similar manner, if the kilovoltage supplied through transformer 13 to the X-ray tube should be increased, this also would increase the speed of charging of condenser 32 through the control effect of the transformer winding 62b. This also would cause the tube 26' to fire sooner so as to stop the exposure.

According to the type or focal spot of the X-ray tube 16 the value or setting of the resistor 70 may be adjusted. If an X-ray tube permitting heavier loading capacity is used, then the value of 70 may be increased so as to allow a greater milliampere-seconds limit. Thus, through the combination of the transformer winding 66b and resistor 70 in the control circuit, one may limit the product of milliamperes times seconds that may be applied to the X-ray tube.

Referring now to Figs. 2 and 3, these circuits provide protection of the X-ray tube against exposures closely following one another and no one of which is sufficient in itself to overload the X-ray tube. It is a fact that the ratings of X-ray tubes are based on a cold anode and if there is insufficient time between successive exposures to cool the anode, then heat is built up in the anode faster than it can be dissipated and the tube may be overloaded. The circuits of Fig. 2 are exactly like those of Fig. 1, with one exception presently to be noted. The lines 73, 78, 76, 71, 39 and 40 are intended to be joined to exactly the same lines of Fig. 1 along the dot-dash line A there indicated, and all of the diagram above the dot-dash line of Fig. 1 is hereby incorporated in Fig. 2.

The change in Fig. 2 consists in the inclusion of a resistance 79 in the circuit including line 39, condenser 32, line 40 and the armature 22b of relay 22. Thus, when no exposure is in progress, the armature 22b does not short-circuit the condenser 32. Instead, the bleeder resistance 79 is

in disconnectable shunt circuit across the condenser 32. Then, when an exposure is shut off, the armature 22b closes the circuit between lines 39 and 40 and the condenser 32 discharges through the resistance 79. This resistance is selected according to the type of X-ray tube used. The value of resistance 79 is made such that the rate of discharge of condenser 32 is equal to the rate of heat dissipation from the anode of the X-ray tube 16.

It results from the above construction that if a second exposure is put on the X-ray tube immediately after the first one, the energy applied to the X-ray tube and the heat applied to the anode thereof keeps on increasing, and if both of these exposures were allowed to run the maximum safe value for a single exposure, the X-ray tube might be overloaded. However, since the resistance 79 discharges condenser 32 at a rate equivalent to the heat dissipation from the anode of X-ray tube 16, the condenser 32 will not be completely discharged at the start of the second exposure. Thus, it will not be possible to put a maximum exposure equivalent to that of the first exposure on the X-ray tube because condenser 32 will reach a voltage sufficient to fire tube 26' quicker than in the case of the first exposure. In other words, it will only be possible to put on a second exposure corresponding to the amount of energy that was dissipated through resistance 79 between the first and second exposures. This makes it impossible to overload the X-ray tube by an accumulation of individual exposures quickly, one after the other.

In Fig. 3 we have shown a modification of Fig. 2 where tube 80 is substituted for the resistance 79, and the rate of energy dissipation from the condenser 32 is controlled by varying the charge on the control grid 80c by suitable means. Since nearly all of the parts and circuits shown in Fig. 3 are like those shown in Figs. 1 and 2, all parts and circuits performing exactly the same function are given the same reference characters. Only two changes are indicated in Fig. 3 as follows.

From a suitable source L₃, L₄, which might be either alternating current or rectified current but in the present instance rectified current is intended, line 81 connects the source L₃ through armature 22c of relay 22 with line 82, relay 25 and line 83 to plate 26b'. Since in this instance rectified current has been indicated at the sources L₃, L₄, once tube 26' has fired, it will remain locked out until the voltage is removed from the tube. In order to accomplish this, the lines 81, 82 are connected through the armature 22c of relay 22. Thus, after an exposure has been completed, button 18 is released and armature 22c returns to its normally open position indicated in Fig. 3, which opens the circuit to the plate 26b' of tube 26' to restore control to the grid 26c'. It will be understood by those skilled in this art that if the source L₃, L₄ were alternating current, then the connection through the armature 22c would be unnecessary and lines 81 and 82 might be short-circuited, as indicated by the dot-dash line 86 of Fig. 3. This improvement might be readily incorporated in Fig. 1 if the source 76, 77 represented a rectified current, and changes in other diagrams involving trigger tubes might be provided with this modification to reset the trigger tube, if desired, as will be readily understood by those skilled in this art.

The second change in Fig. 3 involves the substitution of tube 80 for the resistance 79 of Fig. 2,

as mentioned above. It will be noted that condenser 32 is in circuit with lines 39 and 40 and the armature 22b of relay 22, as before, with the exception that tube 80 is now placed in this circuit replacing resistance 79 of Fig. 2. The cathode 80a of this tube may be of either the hot or cold type. The rate of bleeding off the charge from condenser 32 is controlled by proper selection of the charge on control grid 80c. In the present instance, shunt resistor 84 connected across the source L₃, L₄ is tapped by line 85 to supply the selected voltage to grid 80c.

The operation of Fig. 3 should now be apparent. When a first exposure is terminated, the condenser 32 is not short-circuited, but instead, is connected through lines 39 and 40 and armature 22b with tube 80. The selection of the voltage on grid 80c makes the rate of discharge of condenser 32 equivalent to the rate of heat dissipation from the anode of X-ray tube 16. Here, therefore, as in the case of Fig. 2, a second exposure cannot run for as long a time as the first one unless the time interval between exposures is sufficient to completely discharge condenser 32 which means that the anode of the X-ray tube has had time to become cold.

In Figs. 1 and 3, we have shown the auto transformer 10 with energizing circuit L₁, L₂, and a self-rectified unit. However, those skilled in this art will recognize that in most cases the type of X-ray unit used would be provided with a four-valve-bridge-circuit. Our invention may be used, however, using either a self-rectified circuit, a half-wave rectified circuit, or a full-wave rectified bridge circuit, as will be readily understood.

This application is a division of our copending application Serial No. 685,095 filed July 20, 1946, now Patent No. 2,572,258 for X-Ray Tube Safety Device.

What we claim is:

1. In the combination of an X-ray tube having a high-tension tube energizing circuit including a high-tension transformer having primary and secondary windings and including a filament energizing circuit having a filament transformer with primary and secondary windings, means controlling energization of said X-ray tube including a space discharge tube having control electrode means, a first control transformer having a primary winding in circuit with said high-tension transformer primary winding, a second control transformer having a primary winding responsive to the anode current in said X-ray tube, a capacitance in circuit with said control electrode, and a circuit for charging said capacitance including the secondary winding of each of said control transformers and a resistor selected according to the type and focal spot of said X-ray tube.

2. In the combination of an X-ray tube having a high-tension tube energizing circuit including means for selecting a desired voltage and a filament energizing circuit, means controlling energization of said X-ray tube including a space discharge tube having a control electrode, a capacitance in circuit with said control electrode, and a circuit for charging said capacitance including means responsive to changes in said high-tension circuit independent of said voltage selecting means and means responsive to changes in said filament energizing circuit and a resistor selected according to the type and focal spot of said X-ray tube, said means responsive to changes in said

high-tension circuit including a transformer having one winding connected in parallel with said high-tension tube energizing circuit and said transformer having a second winding in said capacitance charging circuit.

3. In the combination of an X-ray tube having a high-tension tube energizing circuit including means for selecting a desired voltage and a filament energizing circuit, means controlling energization of said X-ray tube including a space discharge tube having a control electrode, a capacitance in circuit with said control electrode, and a circuit for charging said capacitance including means responsive to changes in said high-tension circuit independent of said voltage selecting means and means responsive to changes in said filament energizing circuit and a resistor selected according to the type and focal spot of said X-ray tube, said means responsive to changes in said filament energizing circuit comprising a transformer having one winding connected in the central grounded circuit of said high-tension tube energizing circuit and said transformer having a second winding in said capacitance charging circuit.

4. In combination, an X-ray tube having an anode, electrical operating circuits for said tube, means for timing a period of energization of said tube including an electrical condenser effective to terminate said timing period upon a predetermined accumulation of charge, switch means for connecting said condenser for an accumulation of charge simultaneously with energization of said tube, a bleeder resistance in disconnectable shunt circuit with said condenser for discharging the charge from said condenser substantially coordinated with the rate of dissipation of heat from said anode, and switch means for connecting said resistance in circuit with said condenser during deenergization only of said tube.

5. In combination, an X-ray tube having an anode, electrical operating circuits for said tube, means for timing a period of energization of said tube including an electrical condenser effective to terminate said timing period upon a predetermined accumulation of charge, switch means for connecting said condenser for an accumulation of charge simultaneously with energization of said tube, a space discharge tube in disconnectable shunt circuit with said condenser for discharging the charge from said condenser and having a control electrode, energization means for energizing said control electrode so that discharge of said condenser is substantially coordinated with the rate of dissipation of heat from said anode, and switch means for connecting said space discharge tube in circuit with said condenser during deenergization only of said first-named X-ray tube.
